BY Edgar Tate & Co.

ATTORNEYS.

UNITED STATES PATENT OFFICE.

EDWARD CARNEY, OF HIGH FALLS, NEW YORK.

WINDOW-SCREEN.

No. 901,521.

Specification of Letters Patent.

Patented Oct. 20, 1908.

Application filed December 6, 1907. Serial No. 405,352.

To all whom it may concern:

Be it known that I, EDWARD CARNEY, a citizen of the United States, and residing at High Falls, in the county of Ulster and State of New York, have invented certain new and useful Improvements in Window-Screens, of which the following is a specification, such as will enable those skilled in the art to which it appertains to make and use the same.

10 This invention relates to window screens; and the object thereof is to provide an improved device of this class, the width of which may be adjusted, whereby the screen may be used in window frames of different widths; and with this and other objects in view the invention consists in a device of the class specified constructed as herein-after described and claimed.

20 The invention is fully disclosed in the following specification, of which the accompanying drawing forms a part, in which the separate parts of my improvement are designated by suitable reference characters in each of the views, and in which:—

25 Figure 1 is a side or plan view of my improved screen, Fig. 2 a partial section on the line 2, 2 of Fig. 1, Fig. 3 a section on the line 3, 3 of Fig. 1, Fig. 4 a section on the line 4, 4 of Fig. 1, and;—Fig. 5 a view similar to Fig. 30 2 but showing a modification.

In the practice of my invention I provide two similar frame members *a* comprising parallel side portions *a*² connected by end portions *a*³, and the side portions *a*² of the separate frames *a* are placed together so as to overlap each other. The end portions *a*³ of the separate frames *a* are composed of two separate similar parts secured together as shown in Fig. 4, and the thickness of said 35 end portions of the separate frames is the same as the thickness of the side portions *a*² of said frames where they overlap. The side portions *a*² of the separate frames *a* are also connected adjacent to their free ends by 40 transverse metal strips *b* which are L-shaped in cross section and composed of strips of metal folded longitudinally, and the side portions *a*² of the separate frames *a* are provided in their adjacent faces with wide longitudinal 45 grooves *c* in which are placed strips *d* which fill said groove, and the outer portions of the side members *a*² of the separate frames *a* are provided with grooves *e* which are L-shaped in cross section and which open through the 50 inner face of said portions *a*², and the strips *b*

are provided with end portions *b*² secured between the parts *d* of the side portions *a*² of the separate frames *a*, and the main body parts of said portions *a*², and the strips *b*² are provided with angle members *b*³ which fit in 55 and are movable in the groove *e*.

Secured in each of the frames *a* and between the separate parts of the end portions *a*³ of said frame, and between the main parts of the side portions *a*² thereof and the strips *d* 60 are screens *f* composed of wire mesh or other suitable material, and connected with the transverse metal strip *b* of one of the frames *a* are rods *g* which are also connected with the end portion *a*³ of said frame, and which pass 65 through the flange portion of the transverse strip *b* of the other frame *a* as shown at *g*², and a rod *h* is connected with the transverse strip *b* of the other frame and with the corresponding end portion *a*³ of said frame and 70 passes through the transverse strip *b* of the other frame *a* as shown at *h*².

It will be understood, of course, that by grasping the end portions *a*³ of the separate frames *a*, the said frames may be adjusted 80 laterally to any desired extent, and in this manner my improved screen may be adapted for use in connection with window frames of different transverse widths. It will also be understood that my improved screen is used 85 in connection with window frames and sashes in the usual manner, and is usually placed under the bottom sash which is raised for this purpose.

In Fig. 4 I have shown a modification in 90 which I employ a separate transverse strip or plate *i* with which the end portions *b*² of the transverse metal strips *b* are connected, and these strips or plates *i* are placed between the separate parts of the side portions *a*² of the 95 main frame and have outer end angle members *i*² movable in the slots *e*, and the inner end portions thereof are also bent at an angle as shown at *i*³, and provided with apertures *i*⁴ through which the parts *b*² of the transverse 100 strips *b* are passed and the parts *b*² and *i* are, or may be, secured together in any desired manner, and in Fig. 4 I have shown a nail *i*⁵ used for this purpose, and said nail or nails also serve to aid in securing the parts *d* of the 105 side portions *a*² of the frames *a* to said side portions.

By employing the transverse L-shaped strips *b* as parts of the separate frames *a* and the rods *g* in the manner described, I provide 110

a strong and substantial screen, and one which will be durable in use and will retain its shape.

Having fully described my invention, what I claim as new and desire to secure by Letters Patent, is;

1. A window screen comprising two similar frames each composed of parallel side portions connected by an end member, the side portions of one frame overlapping the corresponding portions of the other frame, and screen material secured in the said frames, the side portions of said frames being also provided with longitudinal grooves which open inwardly and which are L-shaped in cross section, and said side portions of said frames being also connected near their free ends by transverse strips provided at their ends with L-shaped parts movable in said grooves.

2. A window screen comprising two similar frames composed of parallel overlapping side portions connected by end members, the end members being composed of separate parts secured together, and the side portions being provided in their adjacent faces with longitudinal grooves in which are secured separate strips, screen material secured in the said frames between the separate parts thereof, said side portions of said frames being also provided near their free ends with transverse strips having end members which pass between the separate parts of the side portions of said frames and are provided at their outer ends with L-shaped parts mov-

able in longitudinal L-shaped grooves formed in the side portions of the said frames.

3. A window screen comprising two similar frames composed of parallel overlapping side portions connected by end members, the end members being composed of separate parts secured together, and the side portions being provided in their adjacent faces with longitudinal grooves in which are secured separate strips, screen material secured in the said frames between the separate parts thereof, said side portions of said frames being also provided near their free ends with transverse strips having end members which pass between the separate parts of the side portions of said frames and are provided at their outer ends with L-shaped parts movable in longitudinal L-shaped grooves formed in the side portions of the said frames, said transverse strips being L-shaped in cross section and each frame being provided with a rod or rods connected with the end members thereof, and the transverse strip thereof, the said rod or rods of one frame being passed through the transverse strip of the other frame.

In testimony that I claim the foregoing as my invention I have signed my name in presence of the subscribing witnesses this 25th day of November 1907.

EDWARD CARNEY.
